UNITED STATES PATENT OFFICE.

CHARLES W. MUELLER, OF JERSEY CITY, NEW JERSEY.

DRINKING-FOUNTAIN FOR POULTRY.

1,121,528.

Specification of Letters Patent. Patented Dec. 15, 1914.

Application filed May 29, 1911. Serial No. 630,127.

To all whom it may concern:

Be it known that I, CHARLES W. MUELLER, a citizen of the United States, and a resident of Jersey City, in the county of Hudson and State of New Jersey, have invented a new and Improved Drinking-Fountain for Poultry, of which the following is a full, clear, and exact description.

Among the principal objects which the present invention has in view are: to provide a fountain of the character described having means provided in the drinking pan for preventing the spilling or slopping over of the water contained therein; to provide a fountain of the character described so constructed as to facilitate the filling and closing of the fountain; and to provide means for suspending or otherwise anchoring the fountain in operative position.

20 One embodiment of the present invention is disclosed in the structure illustrated in the accompanying drawings, in which like characters of reference denote corresponding parts in all the views, and in which—

25 Figure 1 is a perspective view of a drinking fountain constructed and arranged in accordance with the present invention; Fig. 2 is a perspective view of the fountain showing the parts in separated position; and Fig. 3 is a vertical cross section of the fountain taken on the median line.

As shown in the accompanying drawings, when in the assembled and service position the fountain is provided with a reservoir 8. The reservoir 8 is of cylindrical shape, and is provided with a screw threaded neck 9. The threads formed on the neck 9 register with the threads 10 on the cover 11 provided for the reservoir 8. When the said reservoir 40 is filled with the supply of water for which it is provided it is inverted from the position shown in Figs. 1 and 2 of the drawings, the opening or neck 9 being uppermost. When the reservoir is filled the cover 45 11 is screwed into position upon the said reservoir, when the same may be inverted to assume the position shown in Figs. 1 and 2 of the drawings.

Attached to the cover 11 by means of the supporting rods 12, 12 is the drinking basin 13. The basin 13 is provided with a surrounding inwardly extended flange or rim 14 which overhangs the vertical sides of the basin 13 and diverts the water toward the center of the basin when the same is lifted, as by tilting the basin upward along the said

vertical wall. The rim 14 is shown as a straight rim. It will be understood that this may be curved if desired to throw the water more surely toward the center of the said 60 basin 13.

Rigidly connected with the cover 11 is a pipe 15. The pipe 15 is constructed of a length to extend below the high water mark desired in the basin 13, the end of the said 65 pipe being sufficiently submerged below the surface of the water to check, by hydrostatic pressure, the flow downward from the pipe 15 and the superposed reservoir 8.

It will be understood from the above description that the water originally supplied to the reservoir 8 flows downward through the pipe 15 into the basin 13, and that the water in the basin 13 is maintained at a constant level, the water exhausted therefrom 70 being replenished by the water from the reservoir 8.

The drinking fountain thus constructed may be placed on the floor of a railway car, poultry house, or ground of a poultry yard. 80 When fowl are shipped in crates it is desired that the fountain shall be further secured against being overturned by the crowding of the occupants of the crate, and for this purpose it is provided with rings 16 attached to 85 the upper side of the reservoir 8, as shown in the drawings. These rings are used as anchors for securing twine, straps or other fastening devices which are secured to the upper slats of the crate in any convenient 90 position. It will be understood that if it is desired the straps and fastening devices may be employed to suspend the fountain, the basin 13 resting above the floor.

The handle 17 is suitably attached to the 95 upper side of the reservoir 8. By means of the said handle 17 the drinking fountain is conveniently moved or carried from point to point, filled or empty.

As far as the attendant is concerned the 100 operations upon the drinking fountain are two:—the replenishing of the reservoir 8 and the closing of the fountain. To replenish the reservoir the drinking fountain is upturned so that the reservoir 8 is inverted 105 from the position shown in the drawings. In this position the cover 11 is unscrewed from its engagement with the neck 9 of the reservoir and removed therefrom. The water is now freely poured into the reservoir until 110 filled to the proper level, and the cover 11 and parts connected therewith are then se-

cured in position, engaging the neck 9, when the construction is righted to the position shown in the drawings. The water immediately runs from the reservoir 8 down the 5 pipe 15 into the basin 13 until the predetermined water level has been established in the basin 13, when the hydro-static pressure of the exposed surface of water and the rarification of the air in the reservoir 8 10 above the water therein contained, arrests the flow of water from the reservoir to the basin.

As the chickens now use the water in the basin 13, partially exhausting the same, the 15 supply is maintained by fresh water flowing from the reservoir into the basin.

When handling a fountain thus constructed by means of the handle 17 or the rings 16 the hydro-static column of water is 20 maintained constant and the water is prevented from overflowing the edge of the side walls of the basin 13, the rim 14 operating to deflect or throw the water to the center of the said basin.

25 I claim:

1. A drinking fountain such as described, comprising a basin; a reservoir having an opening, the diameter whereof approximates the diameter of said basin; a cover for said

opening; a plurality of supporting rods permanently and rigidly connecting said basin and said cover, said supporting rods being spaced apart and of sufficient height to provide room to permit poultry to drink from said basin without striking said cover; and 35 a supply pipe in said cover and pendant therefrom to extend adjacent the bottom of said basin.

2. A drinking fountain such as described, comprising a basin; a reservoir having an 40 opening, the diameter whereof approximates the diameter of said basin; a cover for said opening; a plurality of supporting rods permanently and rigidly connecting said basin and said cover, said supporting rods being 45 spaced apart and of sufficient height to provide room to permit poultry to drink from said basin without striking said cover; a supply pipe in said cover and pendant therefrom to extend adjacent the bottom of said 50 basin; and a plurality of hanging rings mounted upon the top of said reservoir for suspending said fountain.

CHARLES W. MUELLER.
